UNITED STATES PATENT OFFICE.

MAX HECHT, OF NEW YORK, N. Y.

DESIGN FOR A WHISK-BROOM HOLDER.

SPECIFICATION forming part of Design No. 17,872, dated November 8, 1887.

Application filed July 14, 1887. Serial No. 244,354. Term of patent 3½ years.

To all whom it may concern:

Be it known that I, MAX HECHT, a citizen of the United States, residing in the city, county, and State of New York, have invented and produced a new and original Design for a Whisk-Broom Holder, of which the following is a specification.

Reference is to be had to the accompanying drawing, forming a part of this specification, in which the figure is a perspective view of my newly-designed broom-holder.

The leading feature of my design consists in a broom-holder presenting the appearance of a necktie.

15 A represents the main body of the broom-holder, made in the form of a necktie, with the crossed pieces *a a*, and the triangular center *b*; and B represents the back loop. In the center piece, *b*, appears the protuberance *d*, in imitation of a scarf-pin. The sides of the body A

show the diagonal edges *f f*, the upper straight edge, *g*, the inner diagonal edges, *h h*, the outer diagonal edges, *i i*, and the diagonal end pieces, *j j*. The whole presents to the eye the appearance of a necktie.

25

I claim—

1. The design for a broom-holder herein shown and described, the same consisting of the crossed pieces *a a*, triangle *b*, and a rectangular back loop, B.

30

2. The design for a broom-holder herein shown and described, the same consisting of the crossed pieces *a a*, the triangular center piece, *b*, protuberance *d* at the center of the triangle, and the rectangular back loop B.

MAX HECHT.
